UNITED STATES PATENT OFFICE

FLOYD L. ROCKE, OF BLOOMINGTON, ILLINOIS

MOTOR STARTER FOR WASHING MACHINES

Application filed September 30, 1927. Serial No. 223,115.

This invention relates to a motor starter for washing machines.

The invention has special reference to manually operable starter means and gear connection from said means to the motor shaft, and including means to permit said manually operated starter means to be reversely actuated to relieve the motor shaft, gear driving means and means for effecting reverse movement of the manually operated starter means.

Referring to the drawings—

Fig. 1 is a plan view of the invention as applied to a motor and driving connections therefor;

Fig. 2 is a side elevation of the same subject-matter disclosed in Fig. 1;

Fig. 3 is an end view of the structure disclosed in Fig. 2, viewed in the direction of the arrow *a* in said figure;

Fig. 4 is a sectional view on the line 4—4 of Fig. 3;

Fig. 5 is a sectional view on the line 5—5 of Fig. 4; and

Fig. 6 is a sectional view on the line 6—6 of Fig. 4.

In the drawings, 10 is a conventional showing of a motor; 11 is a motor shaft; 12 is a band wheel fixed to the motor shaft, and 13 is a belt for driving the band wheel. 14 is a fly wheel fixed to shaft 11. 15 is a housing and support for the operative parts of the motor and also serves as a support for the magneto. 16 is a worm wheel on the shaft 11, cooperating with worm wheel 17 on the magneto shaft.

Referring to Figs. 4 and 5, the driving connection between band wheel 12 and motor shaft 11 is shown, wherein sleeve member 18 of band wheel 12 is shown fixed to shaft 11.

The means for actuating band wheel 12 includes a pulley 19 having laterally projecting hub 20, which is sleeved for support upon sleeve or hub member 18 of band wheel 12, there being provided ratchet members, as 21, on the outer face of said drum sleeve. 22 is a pawl pivoted on stud 23 of band wheel 12 and is adapted to cooperate with ratchet members 21 on hub 20 to cause said band wheel to be revolved for the purpose of turn-

ing shaft 11 when drum pulley is operated in a given direction, but permitting said pulley to be turned in a reverse direction to relieve said band wheel 12. 24 is a belt or strap attached to pulley 19 and extends thereabout, as shown in Fig. 6, and is provided with a gripping handle 25. 26 is a housing for pulley 19, the same being suitably supported from angle arm 30 fixed to a suitable base.

Automatic means are provided for turning pulley 19 in reverse direction from that of its actuation to drive motor shaft 11, such means including an interior drum member 31 fixed to housing 26 by means of bolt 32 and nut 33, whereby said drum is maintained in stationary position. 34 is a wire coil spring supported about the stationary drum 31, one end of said wire constituting the coil being fixed as at 35 to movable pulley member 19 and the other end of said wire being fixed to the stationary drum.

The spring 34 is secured to the inner drum by an eyelet 37 formed on the end of the spring which is secured around the rod 36 which extends through the cup and through the head 38 of the bolt 32 as shown. The rod also extends outwardly as far as the outer edges of the drum 19 so as to prevent outward movement of said drum.

At the beginning of the starting operation as a result of an outward drawing of belt 24, wire coil 34 is substantially free from tension, but as movable pulley 19 is turned to effect turning of shaft 11, a tensioning through extension of said spring coil is effected in reaction against said starting movement of the movable pulley, whereby when such starting movement of the movable pulley is discontinued, reaction of the spring will serve to return movable pulley 19 to its initial or starting position and likewise a similar return of belt member 24.

From the above description, it will appear that the drum driving means is provided, serving when said drum is turned in a given direction, to operate motor shaft 11 through the withdrawal action of a belt attached to said drum, and a return of said drum to initial position is effected through the action

of the coil spring member and the ratchet and pawl connection of said drum with the band wheel.

What I claim is:

1. A device of the character described, comprising, in combination with the rotary shaft of an internal combustion engine, an open end hollow winding drum rotatable coaxially relative to said shaft, pawl and ratchet means releasably connecting said drum and shaft, a spring carrying cup positioned within said drum in spaced coaxial relation thereto, a rod traversing and fixed to said cup with a termination projecting therefrom, supporting means upon which said cup is secured, a coiled tension spring surrounding said cup secured at one end to the projecting termination of said rod and secured at its other end to said winding drum, and a flat flexible traction element secured to and windable around said winding drum.

2. A device of the character described, comprising, in combination with the rotary shaft of an internal combustion engine, an open end hollow winding drum rotatable coaxially relative to said shaft, pawl and ratchet means releasably connecting said drum and shaft, a spring carrying cup positioned within said drum in spaced coaxial relation thereto, a rod traversing and fixed to said cup with a termination projecting therefrom, supporting means upon which said cup is secured, a coiled tension spring surrounding said cup secured at one end to the projecting termination of said rod and secured at its other end to said winding drum, and a flexible element secured to and windable around said drum.

3. A device of the character described, comprising, in combination with the rotary shaft of an internal combustion engine, an open end hollow winding drum rotatable coaxially relative to said shaft, pawl and ratchet means releasably connecting said drum and shaft, a spring carrying cup positioned within said drum in spaced coaxial relation thereto, a rod traversing and fixed to said cup with a termination projecting therefrom, supporting means upon which said cup is secured, a coiled tension spring surrounding said cup secured at one end to the projecting termination of said rod and secured at its other end to said winding drum, and a flexible element secured to and windable around said drum, said projecting termination extending outwardly to a point of alignment with the rim of said drum, to prevent axial movement of said drum in one direction.

4. A device of the character described, comprising, in combination with the rotary shaft of an internal combustion engine, a pawl mounted on said shaft, an open end hollow winding drum rotatable coaxially relative to said shaft and having a ratchet-wheel fixed thereon releasably engaged by said pawl, a spring carrying cup positioned within said winding drum in spaced coaxial relation thereto, a rod traversing and fixed to said cup with a termination projecting therefrom, supporting means upon which said cup is secured, a coiled tension spring positioned around said cup, secured at one end to the projecting termination of said rod and secured at its other end to said winding drum, and a flat flexible traction element secured to and windable around said winding drum.

5. A device of the character described, comprising, in combination with the rotary shaft of an internal combustion engine, a spring-controlled pawl mounted on said shaft, an open end hollow winding drum rotatable coaxially relative to said shaft and having a ratchet-wheel fixed thereon releasably engaged by said pawl, a relatively fixed support adjacent to said winding drum, a spring carrying cup whose head and said support have alined apertures, a bolt having a diametrically apertured head positioned within the cup and engaging the latter, with its stem traversing said alined apertures and secured adjustably to the support, a diametrical pin traversing said cup and the said apertured head, a coiled tension spring end secured to said pin and drum, and a strap secured to and wound on said drum.

In witness whereof I have hereunto affixed my signature.

FLOYD L. ROCKE.
